UNITED STATES PATENT OFFICE.

DAVID B. JONES, OF CHICAGO, ILLINOIS, ASSIGNOR TO METALLURGICAL LABORATORIES, INC., OF CHICAGO, ILLINOIS, A CORPORATION OF ILLINOIS.

SPELTER FURNACE.

Original application filed June 22, 1914, Serial No. 846,466. Divided and this application filed June 3, 1918, Serial No. 237,867. Renewed October 6, 1922. Serial No. 592,844.

To all whom it may concern:

Be it known that I, DAVID B. JONES, a citizen of the United States, residing at Chicago, in the county of Cook and State of Illinois, have invented certain new and useful Improvements in Spelter Furnaces, of which the following is a specification.

The present application is a division of an application, Serial No. 846,466, filed June 22, 1914 (renewed June 20, 1918, Serial No. 239,920), upon which Patent No. 1,292,330 was granted to me January 21, 1919. Said patent relates to a method of treating zinc ore, which method is briefly described hereinafter in connection with my improved furnace in which it is employed. I have also shown and described hereinafter in connection with my furnace a new form of briquette which is particularly adapted for use therein and which is claimed in an application No. 237,868, filed of even date herewith, patented May 9, 1922, No. 1,415,094. Generally speaking, the new method of treating zinc ores in which the invention constituting the subject-matter of this application is employed consists in forming spherical or rounded briquettes of the zinc or other ore being treated and a reducing agent, and rolling them through the furnace, preferably by gravity, the floor of the furnace being inclined for this purpose and the briquettes introduced at the higher end of the furnace and removed or discharged from the lower end, there being preferably a continuous series of briquettes from the upper to the lower end of the furnace so that as those which have experienced sufficient treatment are removed fresh briquettes may be added to the upper end of the series. The briquettes are heated in the furnace to a temperature sufficient to drive off the contained metal. The atmosphere of the furnace is maintained oxidizing so that as the metal is vaporized it is oxidized, and the oxid or fume carried away and separated from the air in any well-known or satisfactory manner. While the furnace which forms the subject-matter of this application is particularly designed and adapted for use in the process just described, it will be obvious from the following specification that it is adapted also in certain of its features for other purposes, and therefore while I have shown and described the preferred

form of the invention in detail and in connection with the reduction of zinc from its ore, it is to be understood that the specific disclosure is for the purpose of exemplification only and that the scope of the invention is defined in the following claims in which I have endeavored to distinguish it from the prior art so far as known to me, without, however, relinquishing or abandoning any portion or feature thereof.

In the accompanying drawing forming a part of this specification, Fig. 1 is a longitudinal vertical section of a furnace embodying my invention; Fig. 2 a transverse vertical section thereof on the line 2—2 of Fig. 1; Fig. 3 a transverse section of an inclined plane on the line 3—3 of Fig. 1, and Fig. 4 a central section through one of the briquettes for the treatment of which my furnace is more particularly designed. Each part is identified wherever it may occur throughout the several views by the same reference character.

As clearly shown in Fig. 1, the furnace, including its hearth, roof and side walls, is built on an incline, the angle being such as to ensure that the briquettes when unsupported at the lower end of the hearth will move by gravity in the direction thereof. The hearth is formed of a series of longitudinal walls or piers A spaced slightly apart and maintained in spaced relation by bricks a interposed at suitable intervals between said piers. The upper edges of the walls or piers are chamfered as shown in Fig. 2 so that each pair of adjacent piers forms a guide, trough or runway down which the spherical briquettes B may travel toward the discharge end of the furnace. These piers or walls, as well as the roof, side and end walls, may be made of any of the usual refractory materials employed in furnaces. In the construction shown in the drawings the runways so formed are nine in number and at the upper end of each the wall of the furnace is provided with a charging opening C, and at the lower end of the furnace the wall thereof is provided with a discharge door D for each of the runways and, as heretofore stated, in an ordinary operation of the furnace the lowermost briquette is discharged as soon as it has had sufficient heat treatment to practically drive off the contained zinc, a new briquette being added at the upper end of the row. The

furnace is preferably heated by gas, there being a series of transverse chambers X arranged at suitable intervals along the length of the furnace through the piers, which 5 chambers receive transverse perforated gas pipes G² and similar but somewhat larger air pipes F², there being an air and a gas pipe for each chamber arranged adjacent each other. Upon one side of the furnace 10 and extending longitudinally thereof is an air pipe F' for supplying the transverse perforated pipes with air and on the other side of the furnace is a longitudinal pipe G' connected to some suitable source of fuel gas 15 for supplying the pipes G² therewith. The air pipe might be connected immediately to some source of air, but preferably the air supplied thereto is preheated. This may be done as in the specific form of invention 20 illustrated in the drawing, by constructing a chamber E at the lower end of the furnace into which the briquettes are received from the furnace after they have been highly heated. The air pipe F' is connected to this 25 chamber and a fan F supplies air to the chamber where it is highly heated by the briquettes contained therein before passing to the pipe F'.

I also maintain a highly oxidizing atmosphere in the furnace so that the zinc as it is volatilized is converted into the oxid in which form it is conveyed out of the furnace and collected. In order to furnish an adequate supply of highly heated air for this 30 purpose the chamber E is connected to the furnace chamber by an elbow pipe E', the flow of air through which is controlled by a valve E². From the upper end of the furnace leads a flue or conduit I which is connected to any suitable or well-known means 35 for collecting zinc fumes or oxid. The heated air is driven continuously from the chamber E through the furnace, oxidizing the vaporized zinc and conveying it away as 40 above described.

The zinc ore to be treated is made into briquettes B which preferably consist of a core or main body of a mixture of zinc ore and reducing agent, such as powdered coal, 45 with an inert binder such as bauxite or other clayey material, these ingredients being mixed with water in order to agglutinate them and then molded under high pressure into spherical form. The briquette is then 50 covered with a relatively thin coating of refractory material such as fire clay which may be applied in the form of a slip. The briquettes are slowly and thoroughly dried to drive off all water before being introduced 55 into the furnace. The drying may be accomplished either after the fire clay slip has been applied or the briquettes may be dried before the covering is applied and then again dried after such application. Preferably a temperature in excess of 225° is em- 60

ployed, it being desirable, however, to keep the temperature so low that the briquettes will not be disintegrated by the evolution of steam.

I claim:

1. In a device of the class described, a heating chamber, a sole or hearth of which is composed of spaced longitudinally extending walls the upper edges of which form guides for the material to be treated, and means for discharging heated gases into the spaces between said walls. 70

2. In a device of the class described, a heating chamber, a floor or sole therefor formed of a series of vertical walls extending longitudinally of the chamber the tops of the walls being inclined from end to end of the furnace and openings adjacent the upper and lower ends of said walls for charging and discharging the chamber and 80 means for discharging heated gases into the space between said walls. 85

3. In a device of the class described, a heating chamber, a series of spaced longitudinally extending walls forming the sole 90 thereof and means for discharging heated gases into the spaces between said walls. 95

4. In a device of the class described, a heating chamber, a series of spaced longitudinally extending walls constituting the 95 hearth or sole thereof, there being transverse chambers extending through said walls, and means for supplying said chambers with gas and air to support combustion. 100

5. In a device of the class described, a heating chamber, a series of vertical walls the tops of which are longitudinally inclined spaced apart laterally of the furnace and constituting the sole or hearth there- 105 of, the upper edges of said walls being chamfered, openings in the upper and lower ends respectively of the furnace in register with the spaces between said walls for introducing the material to be treated to the hearth, and means for supplying heated gases to the spaces between said walls. 110

6. In a device of the class described, a heating chamber, an inclined hearth in said chamber, charging openings at the upper end of said chamber, discharge openings at the lower end thereof, a storage chamber into which the material to be treated is discharged from said chamber, means for introducing air into said storage chamber, 115 burners for heating the heating chamber and conduits for supplying said burners with heated air from the storage chamber. 120

7. In a device of the class described, a heating chamber, a hearth in said chamber, charging openings at one end of said hearth, discharge openings at the other end of said hearth, a storage chamber into which said discharge openings lead, burners for heating the heating chamber, means for sup- 125 130

plying said burners with gas, a fan for forcing air into said storage chamber and pipes for conducting the heated air from said storage chamber to the burners.

- 5 8. In a device of the class described, a heating chamber, a hearth in said chamber, charging openings at one end of said hearth, discharge openings at the other end of said hearth, a storage chamber into which
10 said discharge openings lead, burners for heating the heating chamber, means for supplying said burners with gas, a fan for forcing air into said storage chamber and a conduit for conveying the heated air from
15 said storage chamber to the heating chamber.

9. In a device of the class described, an inclined heating chamber, a hearth having openings extending substantially longitudinally thereof for supplying heating gas 20 to the chamber, burners communicating with said openings, charging openings at one end of said chamber and discharge openings at the other end of said chamber, a storage chamber with which said discharge openings communicate, means for supplying said storage chamber with air and means for conducting said air from the storage chamber to the heating chamber and to said burners. 25

DAVID B. JONES.
